WIRE PUSHING AND PULLING TOOL

Theodor Mistelski, Alliance, Ohio

Application August 31, 1931, Serial No. 560,472

12 Claims. (Cl. 175—376)

The invention aims to provide an exceptionally simple and inexpensive, yet a convenient and efficient tool for pushing or pulling wires through conduits, the tool being particularly adaptable for making electrical installations.

In carrying out the above end, further objects are to provide a tool which allows gripping of the wire whenever desired, allows release of the wire at any moment, and may be operated with either short or long strokes, as may be most conveniently accomplished.

A still further object is to provide for frictionally holding the wire after each operative stroke of the tool so that said wire cannot slip during the idle or return strokes of said tool.

Yet another aim is to provide a tool which may be quickly and easily applied to or removed from the wire.

With the foregoing in view, the invention resides in the novel subject matter hereinafter described and claimed, description being accomplished by reference to the accompanying drawings.

Fig. 1 is a side elevation showing one form of construction.

Fig. 2 is a central vertical longitudinal sectional view.

Figs. 3, 4 and 5 are sectional views on lines 3—3, 4—4 and 5—5 respectively of Fig. 2.

Fig. 6 is a fragmentary rear elevation.

Fig. 7 is a side elevation showing a slightly different construction.

Fig. 8 is a transverse sectional view on line 8—8 of Fig. 7.

Fig. 9 is a fragmentary perspective view showing a still further variation.

Fig. 10 is a central longitudinal sectional view showing yet another form of construction.

Fig. 11 is a transverse sectional view on line 11—11 of Fig. 10.

In the drawings above briefly described, 12, 13 and 14 denote three sections of a tube of rigid nature, the end 15 of said tube being adapted to be held against one end of the conduit by hand, or possibly to be held by coupling it to said conduit. While the tube is shown formed from three sections, this is of course not essential, as a one-piece structure could well be used. The wire passes through the tube and in order to laterally distort said wire and thus frictionally hold it during the idle strokes of the pushing or pulling means hereinafter described, the tube is provided with a curved portion, said portion being the tube section 14 in the present disclosure.

The entire tube 12—13—14 may be provided with a slot 16 extending from end to end thereof

as shown in Figs. 1, 2 and 5, or said tube may be of continuous form in transverse section as illustrated in Figs. 7 and 8. When the slot 16 is employed, it permits the tube to be moved laterally onto or from the wire, which is often more convenient than sliding said tube along the wire to apply or remove it.

Slidable in the major portion of the above described tube, is a reciprocatory rod 17 preferably having an enlarged head 18 at its rear end. This rod is provided from end to end with a wire-receiving passage and said passage may either be in the form of a laterally opening groove 19 as shown in most of the views, or in the form of a mere bore 20 as seen in Fig. 9. The advantage for using a groove 19 instead of a mere bore 20, is the same as that existing in connection with the slot 16.

The head 18 is provided with a fixed and a movable handle which jointly form a hand grip by means of which the rod 17 may be reciprocated, and wire-gripping means is actuated by movement of the movable handle toward the fixed handle, and is releasable by relieving the pressure on said movable handle. In most forms of construction herein disclosed, the fixed handle 21 and the movable handle 22 project laterally from the head 18, forming a convenient structure simulating a pistol grip. In the construction shown in Figs. 10 and 11 however, the fixed handle 21' and the movable movable handle 22' project rearwardly from the head 18. In either form of construction, the inner end of the movable handle is pivoted at 23 in a recess 24 formed in the head 18, and near its pivot, said movable handle is provided with a lug 25 which co-acts with one side of the wire passage in gripping the wire when the movable handle is moved toward the fixed handle, by jointly gripping both of said handles. By releasing the pressure on the movable handle however, the wire is released.

In the form of construction shown for instance in Fig. 2, a spring 26 moves the handle 22 rearwardly to released position, and a pin 27 extending across the recess 24, limits such movement of said handle. This same pin preferably holds the inner end of the spring 26 against the bottom of the recess 24.

When a longitudinally slotted tube and rod are employed, such as seen in Figs. 1, 2, 3 and 5, said tube and rod are relatively turned after application of the tool to the wire, so as to bring the slots 16 and 19 out of alignment with each other as illustrated in Fig. 5, overcoming liability of

extending from the body portion, a lever mounted on the body portion and co-operating with the walls of the bore in gripping an article, said finger piece and lever providing a pistol grip to operate the device, and a snake-guiding tube secured to the body portion and through which the snake extends.

12. In a device substantially as shown, a body portion, a pistol hand grip on the body portion and including a pivoted member co-operating with the body portion for gripping a fish wire, in combination with an advanced feeding tube for supporting said fish wire. 80
